TOOL FOR BREAKING CONCRETE AND
THE LIKEVincent Neamand, Warminster Township,
Bucks County, Pa.

Application November 7, 1949, Serial No. 125,857

3 Claims. (Cl. 262—33)

1

This invention relates to tools for breaking concrete and the like, and more particularly to an improved percussively operated tool for this purpose.

It is the principal object of the present invention to provide a tool for breaking concrete and the like which is capable of use for impact penetration, cutting and breaking, as well as for a leverage effect upon the edge of penetrated material.

It is a further object of the present invention to provide a percussively operated tool for breaking concrete and the like having an improved shape with which advantages not heretofore obtained are made available.

It is a further object of the present invention to provide a percussively operated tool for breaking concrete and the like having a forward tapered end portion connected to an intermediate body portion of particular shape at the end of which a connecting end or shank is provided for engagement with a socket in the chuck of a pneumatic hammer.

Other objects and advantageous features of the invention will be apparent from the specification and claims.

The nature and characteristic features of the invention will be more readily understood from the following description, taken in connection with the accompanying drawings forming part hereof, in which:

Figure 1 is a side elevational view of a tool in accordance with the present invention;

Fig. 2 is an end elevational view thereof;

Figs. 3, 4, 5, 6, and 7, are transverse sectional views, enlarged, taken respectively on the lines 3—3, 4—4, 5—5, 6—6, and 7—7; of Fig. 1.

It should, of course, be understood that the description and drawings herein are illustrative merely, and that various modifications and changes may be made in the structure disclosed without departing from the spirit of the invention.

Referring now more particularly to the drawings, the tool in accordance with the present invention preferably includes an elongated body 10 having at the forward or working end thereof a pair of opposed tapered or converging end faces 11, forming a chisel point, and, if desired, at the forward ends thereof the tool may be sharpened to provide inclined cutting faces 12. The faces 11 may, if desired, have a slight curvature between their vertical margins as illustrated in Fig. 7. At the opposite end of the body of the tool, a shank 13, preferably of hexagonal cross-

2

section, is provided for engagement with a complementally formed socket in the chuck of a pneumatic hammer (not shown), and a collar 14 of conventional type may be provided at the inner end of the shank 13. Between the end faces 11 and the collar 14, an intermediate portion 16 is provided, preferably bounded by a pair of flat parallel side faces 15 which extend to the forward end or faces 12 of the tool body 10, and by a pair of opposed side marginal faces 17 which extend between and connect the side faces 15. The side faces 17 may be of any preferred shape in transverse cross-section but are preferably arcuate as illustrated in Fig. 6.

At the inner terminal portions of the side faces 15 and 17 an integral cylindrical connecting portion 18 is provided which extends to the shank 13 and with which it is integral.

The side faces 17 are preferably gradually tapered with a converging taper from their junction with the inner terminals of the faces 12 to the cylindrical portion 18. It will thus be seen that there is a larger cross-sectional area of the body 10 at the inner ends of the faces 11, as indicated in Fig. 6, with a decreasing cross-sectional area between the parallel faces 15 to the junction of the faces 15 and 17 with the connecting portion 18.

The tool is preferably made of a single piece 30 of alloy steel capable of being hardened throughout to obviate mushrooming of the point in use, and to permit of regrinding to the desired shape upon the occurrence of wear.

In the use of the tool, the same is operated with 35 its end faces 11 and with its faces 12 in contact with the material to be penetrated and broken, and suitable impacts are imparted thereto by a pneumatic hammer in the usual manner. As the faces 11 and 12 penetrate the material, a wedging effect is obtained by reason of the inclination of the faces 11 which tends to break apart the material as penetration occurs. Upon further entry of the tool into the material to be broken, the inner ends of the end faces 11 may penetrate below the outer surface thereof, and the tool may be employed as a bar or lever with the application of force parallel to the side faces 15 for breaking up and splitting the material. As the inner ends of the faces 11 pass below the outer surface of the material, being penetrated, there is no binding effect and the tool may be readily withdrawn, if desired or required, to start a new hole. If, at any time, the tool requires resharpening, this may be readily effected with-

out substantial change from the initial shape by grinding.

It will be noted that between and with the parallel side faces 15 a maximum cross-sectional area is provided at the inner ends of the terminal faces 11 and a minimum cross-sectional area is provided at the outer end of the connecting portion 18.

I claim:

1. In a percussively operated tool for breaking concrete and the like, an elongated body portion having an actuating shank at one end and a pair of converging terminal faces at the other end thereof, said body from said other end thereof and from the outer ends of the terminal faces being bounded by a pair of parallel side faces decreasing in width from the inner ends of said terminal faces, said parallel faces being connected by side faces converging from the inner ends of the terminal faces.
2. In a percussively operated tool for breaking concrete and the like, an elongated body portion having an actuating shank at one end and a pair of converging terminal faces at the other end thereof, said body from said other end thereof and from the outer ends of the terminal faces being bounded by a pair of flat parallel side faces, said parallel faces being connected by side faces transversely arcuate and converging from the inner ends of the terminal faces.
3. In a percussively operated tool for breaking concrete and the like, an elongated body

portion having a shank at one end and a connecting portion extending from said shank towards the other end, the other end of said body portion having a pair of converging terminal faces, the body portion transversely of said terminal faces being bounded by a pair of parallel side edge faces and, on sides corresponding with said end faces, being bounded by connecting edge faces connecting the margins of the parallel faces, said connecting edge faces and the margins of said parallel faces converging from the inner ends of said terminal faces to said connecting portion, and said body portion having a maximum cross sectional area at the inner ends of said terminal faces and a minimum cross sectional area at said shank connecting portion.

VINCENT NEAMAND.
